(57) **CLAIM**

The ornamental design for a keypad for a communication device, as shown and described.

DESCRIPTION

FIG. 1 is a perspective view of an ornamental design for a keypad for a communication device; and,

FIG. 2 is a front view thereof.

The broken line showing of the remainder of the communication device is directed to environment and is for illustrative purposes only; the broken lines form no part of the claimed design.

1 Claim, 2 Drawing Sheets

FIG. 1

FIG. 2
